SELF-TIGHTENING CLIP FOR APPLYING
SHEATHING TO METALLIC MEMBERS

Gerald G. Greulich, Mount Lebanon, Pa.

Application September 28, 1938, Serial No. 232,204

4 Claims. (Cl. 189—35)

The present invention relates to building structures and, more particularly, to a self-tightening clip for applying wooden or other type of sheathing to metallic beam members.

5 An object of the present invention is to provide a self-tightening clip for obtaining a permanent, tightly clamped, engagement between structural members and sheathing.

10 A further object of the present invention is to provide a self-tightening clip so constructed and arranged that the sheathing to which it is attached may be rigidly and permanently fastened to structural members by a single fastening device.

15 Other objects and advantages will become apparent as the description proceeds and reference is had to the accompanying drawing, in which:

20 Figure 1 is a plan of the clip of the present invention, showing its manner of attachment to a structural beam member;

Figure 2 is a front elevation of Figure 1;

Figure 3 is an end view, looking from the right of Figure 2 to show the doubled-back portion of the clip;

25 Figure 4 is a view similar to Figure 2, showing the position of the clip after the nail has been driven into the sheathing; and,

Figure 5 is an end view, looking from the right of Figure 4.

30 The self-tightening clip of the present invention is so formed from a sheet blank as to produce a main body 2 having laterally extending integral flanges at each end thereof forming clamping members 3. Flanges 4 adjacent each

35 end of said main body are bent downwardly at right angles thereto for abutting the edge or side of the sheathing, while a flange 5, centrally located of said main body 2, is bent upwardly at right angles to the main plane thereof to abut the adjacent sheathing member.

40 As shown in Figure 2, the main body is bent or doubled-back upon itself to provide a folded portion 6 between the ends thereof. This folded portion 6 is provided with a plurality of aligned openings 7 through which is adapted to pass a nail or other securing member 8. The openings 7 in the two upper folds are elongated to provide a limited movement of said main body 2 so that

45 upon impact upon the nail or securing member 8, the folded portion 6 of said main body will be compressed from a position shown in Figure 2 to the position shown in Figure 4, the clamping members 3 are moved inwardly toward each other until the grooved or inclined portions 3a of said

clamping members tightly engage the flange of the structural member 12.

5 In applying the clip, the main body 2 is placed over the top or edge of the sheathing 10 with the flanges 4 contacting the side of said sheathing and the right hand clamping member 3 positioned upon the flange of said structural member, after which, the nail or securing member 8 is inserted through the aligned openings in the doubled-back or folded portion 6 and driven perpendicularly into said sheathing 10 until the folded portion 6 is compressed in superimposed relation, as shown in Figure 4, which action results in moving the left hand flanged member 3 to the right due to the elongated openings in the 15 two upper folds so as to securely engage the clamping members with the flange of the structural beam member. After this operation is completed, an adjacent sheathing member 14 is then placed in position upon the main body 2 and in 20 engagement with the upwardly extending flange 5, and secured thereto by driving a nail or other securing member through the opening 9 in order to securely retain said sheathing member upon the structural beam member.

25 The construction of the present invention, as hereinabove described, offers many advantages over the clips now in use. It is the usual practice to use a flat clip which is secured to the edge of the sheathing by nails and the like and which, 30 when so secured, extends beyond the inner edge of the sheathing in a portion which is provided, adjacent and parallel to this edge, with a V-shaped slot designed to produce a wedge-engagement with one side of the structural beam outer 35 flange. This construction requires an additional clip for the other side of the beam flange. Under such a construction, the permanency of such an attachment is subject to variable performance of the person making the installation and, should the slotted portion of the clip be engaged with the beam flange in any other than a perpendicular position with respect thereto, the sheathing attached to the clip will not be rigid. However, 40 under the present construction, these objections 45 are overcome and there is provided a self-tightening clip whereby sheathing may be rigidly and permanently secured to metallic beam members in an economical manner.

50 While I have shown and described specific embodiments of the present invention, it will be seen that I do not wish to be limited exactly thereto, since various modifications may be made without departing from the scope of the invention as defined by the following claims.

I claim:

1. A self-tightening clip for attaching sheathing to structural members comprising a main body, flanges on each end of said main body, said main body provided with a folded portion between the ends thereof, sheathing engaging flanges formed on said main body, aligned openings in said folded portion of said main body and means for compressing the folded portion of said main body whereby said end flanges will be brought into engagement with the flange of the structural member to rigidly interlock said clip thereto.

2. A self-tightening clip for attaching sheathing to structural members comprising a main body member, laterally extending flanges formed on each end of said body member, said main body member having a portion doubled-back upon itself between the ends thereof, aligned openings formed in said doubled-back portion, means for attaching said main body member to a sheathing member, said end flanges adapted to rigidly interlock with the flange of a structural member when said doubled-back portion of said main body member is compressed.

3. A self-tightening clip for attaching sheathing to structural members comprising a main

body, laterally extending flanges formed on each end of said main body, said main body provided with a doubled-back portion between the ends thereof, sheathing engaging flanges formed on said main body at right angles to the main plane thereof, aligned openings in said doubled-back portion, means for securing said clip to a sheathing member, said end flanges rigidly interlocking with the flange of a structural member when said doubled-back portion is compressed in securing the clip to said sheathing.

4. A self-tightening clip for attaching sheathing to structural members comprising a main body, laterally extending flanges formed on each end of said main body, said main body provided with a doubled-back portion between the ends thereof, flanges formed on said main body at right angles to the plane thereof, aligned openings in said doubled-back portion, means for securing said clip to a sheathing member, said end flanges rigidly interlocking with the flange of a structural member when said doubled-back portion is compressed in securing the clip to said sheathing, and means for securing sheathing to one of said right-angled flanges.

25

GERALD G. GREULICH.
